UNITED STATES PATENT OFFICE.

CLARENCE J. RODMAN AND CLEMENT J. BATES, OF ALLIANCE, OHIO, ASSIGNORS TO THE BUCKEYE JACK MANUFACTURING COMPANY, OF ALLIANCE, OHIO, A CORPORATION OF OHIO.

LIFTING JACK.

Application filed April 26, 1926. Serial No. 104,514.

This invention relates to a multiple lift jack of that type wherein a plurality of screws are employed and are arranged to act simultaneously to effect a maximum lift more than twice the height of the closed jack. Our object is to provide such a jack in a simple and efficient form, which may be cheaply manufactured, shall be very compact when closed and may be readily extended. Our invention is hereinafter more fully explained in connection with the drawings, which illustrate a preferred embodiment thereof, and its essential characteristics are summarized in the claims.

In the drawings Fig. 1 is a vertical central section of one form of our jack collapsed; Fig. 2 is a plan thereof, partly broken away; Fig. 3 is a vertical central section in a plane at right angles to Fig. 1 (as indicated by the line 3-3 thereon) showing the jack extended; Fig. 4 is a horizontal section on the line 4-4 of Fig. 1.

The particular embodiment shown in the drawing comprises essentially five members as follows:

First: A base member, as 11, rigidly carrying an upstanding hollow screw 10, with external threads 12, and rigidly carrying around such screw and some distance beyond it, a guiding member 14.

Second: A screw 20 having external threads in the reverse direction from the threads 12 of the screw 10, this inner screw being of a smaller diameter and slidably sliding freely within the bore of the screw 10.

Third: A sleeve 30 having a head portion 31 internally threaded to engage the threads 21 of the screw 20 and having a skirt portion depending between the stationary screw 11 and the guiding member 14, and provided adjacent its lower end with threads 32 to engage the stationary screw 10. The head 31 is formed with a suitable gear 35 whereby the sleeve may be driven.

Fourth: A rotatable driving pinion 40 meshing with the gear 35, and having suitable means by which it may be rotated.

Fifth: A suitable housing 50 providing bearing for the pinion 40 and the gear 35 and having a depending skirt 52 which telescopes with the guiding member 14, the skirt and guiding member preventing the

housing rotating while allowing it to rise as the jack is extending. The housing has a lug 55 occupying a keyway 25 in the screw 20.

It follows from the above described construction that the driving pinion 40 is in a fixed angular position with reference to the base but stands at various elevations above it. Now assuming the jack to be collapsed, as the pinion is rotated, (as for instance by a square torsion rod 42 engaging a square socket 43 in the pinion) the gear 35 will be rotated, whereupon the screw 50 (which cannot rotate by reason of the lug or lugs 55 occupying the keyway or keyways of the screw) will rise with reference to the nut member 30; at the same time this nut member itself will rise on the stationary screw 10, thus giving a double lift to the upper end of the screw or to a load saddle 23 mounted thereon. A limit of extension may be readily provided by means of a pin 27 carried by the innermost screw, which pin engages the underside of the driving sleeve member at the uppermost position of the screw. This uppermost position of the screw 20 with reference to the sleeve member 30 is accompanied by substantially the uppermost position of the sleeve member 30 with reference to the stationary screw 10, as shown in Fig. 3.

It is essential that the direction of threading of the stationary screw 10 be opposite to that of the movable screw 20, one being a right hand thread and the other a left hand thread. We have shown the stationary screw as having the right hand thread and the traveling screw the left hand thread, but of course this condition could be reversed. Likewise the pitch of the screws may be the same in degree, or different if desired. If different, the screw with the steeper pitch will have a greater travel, than the screw of lesser pitch, for a given rotation of the driving sleeve. By making the innermost screw of slightly steeper pitch, we are enabled to cause it to lift an amount substantially the same as the height of the stationary screw while the sleeve lifts a similar amount reduced by the height of the threaded region adjacent the lower end of the sleeve. This is the operation illustrated in the drawings, but, as stated, the relation of the degree of pitch of the two screws may be varied if desired.

In the drawings, we have shown the screw 10 as formed integrally with the base 11 and we have shown the stationary guiding member as a sleeve 14 riveted to the base by means of integral tongues 15 of such sleeve. This particular way of connecting all these rigid parts may be varied as desired. They can all be cast as a unit, or the sleeve 14 might be integral with the base and the screw 10 made separate and secured in position.

We have also shown a base plate 18 inset in the base 11 and covering the bore of the stationary screw, this plate being secured to the same riveted tongues 15 which hold the guiding sleeve 14.

The guiding sleeve 14 and the skirt 52 of the housing are shown as hexagonal tubes, this being a convenient form of a non-circular member, allowing the telescoping while preventing rotation.

As shown, the housing 50 is a two part member diametrically separable and held together in practice by bolts 56. The tube 52 is shown as provided at its upper end with an outwardly extending flange 57 which occupies an annular recess in the housing.

The driving pinion member 40 is shown as provided with a cylindrical shank 45 occupying the bearing provided by the housing members and having a collar 46 beyond that housing, the pinion itself being substantially at the inner face of the housing.

In assembling the parts, the base member, the stationary screw, the stationary guiding sleeve and the closing base plate 18 may all be rigidly formed before such assemblage. The stop pin 27 may be put in place in the screw 20, and then this screw, with its load saddle removed, inserted from the bottom upwardly into the head of the rotatable sleeve member and thereafter the saddle applied.

Now, the housing skirt 52 may be dropped into position outside of the guiding sleeve 14; then the rotatable sleeve member carrying the inner screw screwed down to its lowermost position on the stationary screw, as shown in Fig. 1; then the inner screw if it is not already at the bottom, rotated to that position; thereafter one-half of the housing 50 is applied, the pinion is put in place in such one-half in mesh with the gear and then the other one-half of the housing is installed, the screw 20 being positioned so that the housing lugs 55 occupy the keyways 25. Now, the bolts 56 put into place and the nuts tightened. When the two halves of the housing are thus bolted together, they provide proper bearings for the gear 35 and for the driving pinion 40 and also tightly clamp the depending skirt 52.

It will be seen from an inspection of Fig. 1 that our jack is extremely compact, there being very little waste space over the theo-

retic minimum; likewise in its extended position the jack closely approximates the maximum theoretic extension.

Having thus described our invention, we claim:

1. In a jack of the character described, the combination of a base, a hollow externally threaded screw rigidly carried thereby, a second externally threaded screw freely slideable within the bore of the stationary screw, a sleeve embracing said screws and threaded at the lower end on the stationary screw and at the upper end on the traveling screw, a gear on said sleeve, a pinion meshing with the gear, a housing carrying the pinion and telescoping sleeves surrounding the screws and forming a connection between the housing and the base, means for preventing the housing sleeve rotating on the base sleeve, and means for preventing the second screw rotating with reference to the housing.

2. In a jack of the character described, the combination of a base, a hollow externally threaded screw rigidly carried thereby, an externally threaded screw freely slideable within the bore of the stationary screw, a sleeve embracing said screws and threaded at the lower end on the stationary screw and at the upper end on the traveling screw, driving mechanism for the sleeve mounted in a housing, telescoping sleeves surrounding the screws and forming a connection between the housing and the base and a lug on the housing occupying a vertical keyway in the inner screw.

3. In a jack of the character described, the combination of a base, a stationary externally threaded hollow screw rigidly carried thereby, a sleeve rigidly carried by the base surrounding the screw some distance beyond it to leave a space between them, an externally threaded screw freely slideable within the bore of the stationary screw, the threads of the two screws being of opposite direction, a rotatable sleeve having a portion occupying the space between the stationary screw and the stationary sleeve, said sleeve having a threaded engagement near the lower end with the stationary screw and at the upper end with the traveling screw, mechanism for rotating said sleeve, a housing carrying said mechanism, said housing having a depending tubular skirt which telescopes with the stationary base sleeve.

4. In a jack of the character described, the combination of a base, a hollow vertical externally threaded screw rigidly mounted thereon, a hollow sleeve of non-circular cross-section rigidly mounted on the base around the stationary screws, a traveling screw freely occupying the bore of the stationary screw, a rotatable sleeve adapted to extend into the space between the stationary screw and the stationary sleeve, and having near its lower end threads engaging

the stationary screw and near its upper end threads engaging the traveling screw, means for driving said rotatable sleeve, a housing providing bearings for the driving means, and a non-circular skirt carried by the housing and having a telescoping engagement with the non-circular stationary sleeve.

5. In a jack of the character described, the combination of a base, a hollow vertical externally threaded screw rigidly mounted thereon, a hollow sleeve of non-circular cross-section rigidly mounted on the base around the stationary screw, a traveling screw freely occupying the bore of the stationary screw, said inner screw having its threads in the opposite direction from those of the stationary screw and provided with a vertical keyway, a rotatable sleeve adapted to extend into the space between the stationary screw and the stationary sleeve, and having near its lower end threads engaging the stationary screw and near its upper end threads engaging the traveling screw and having near its upper end a gear, a rotatable pinion meshing with said gear, a housing

providing bearings for the gear and pinion, said housing having also a lug occupying the keyway in the inner screw, and a non-circular skirt carried by the housing and having a telescoping engagement with the stationary non-circular sleeve.

6. In a jack of the character described, the combination of a base, a stationary screw carried thereby, a traveling screw adapted to telescope with the stationary screw, said screws having their threads extending in the opposite direction, a rotatable sleeve embracing and engaging with screws, mechanism for rotating the sleeve, a separable housing for said mechanism, and a sliding connection between the housing and the base of the jack comprising a stationary non-circular sleeve carried by the base and a coacting non-circular sleeve carried by the housing, said non-circular sleeves surrounding the stationary screw.

In testimony whereof, we hereunto affix our signatures.

CLARENCE J. RODMAN.
